(57) **CLAIM**

The ornamental design for a breast pump accessory, as shown and described.

DESCRIPTION

The file of this patent contains at least one drawing executed in color. Copies of this patent with color drawing(s) will be provided by the Office upon request and payment of the necessary fee.

FIG. 1 is a front perspective view of a first embodiment of a breast pump accessory showing the claimed design;

FIG. 2 is a front view thereof;

FIG. 3 is a rear view thereof;

FIG. 4 is a top view thereof;

FIG. 5 is a bottom view thereof;

FIG. 6 is a right side view thereof;

FIG. 7 is a left side view thereof;

FIG. 8 is a rear perspective view thereof;

FIG. 9 is another front perspective view thereof;

FIG. 10 is a front perspective view of a second embodiment of a breast pump accessory showing the claimed design;

FIG. 11 is a front view thereof;

FIG. 12 is a rear view thereof;

FIG. 13 is a top view thereof;

FIG. 14 is a bottom view thereof;

FIG. 15 is a right side view thereof;

FIG. 16 is a left side view thereof; and,

FIG. 17 is a rear perspective view thereof.
